UNITED STATES PATENT OFFICE

112,426

DESIGN FOR A SLIDE FASTENER

Theodore A. Hersh, Franklin, Pa., assignor to
Joy Fastener Company, Franklin, Pa., a corpo-
ration of Pennsylvania

Application October 13, 1938, Serial No. 80,430

Term of patent 14 years

To all whom it may concern:

Be it known that I, Theodore A. Hersh, a citizen of the United States and residing at Franklin, in the county of Venango and State of Pennsylvania, U. S. A., have invented a new, original, and ornamental Design for a Slide Fastener, of which the following is a specification, reference being had to the accompanying drawing, forming a part thereof, wherein the figure is a plan view of a slide fastener of conventional thickness illustrating the present design.

As is readily apparent from the drawing, the slide fastener consists of two tapes or stringers each having a series of interlocking elements along one edge thereof, which are adapted to be

moved into and out of engagement with the interlocking elements on the other tape, by means of a slider. Each tape is configured with a series of longitudinally spaced bars or chevrons. The bars on each tape are of the same width and the spacing between the bars is the same throughout the length of the tape. Each tape is also configured with a series of spaced blocks which close the spaces between the bars on each side of the tape.

I claim:

The ornamental design for a slide fastener, as shown and described.

THEODORE A. HERSH.
